CLAIM

The ornamental design for an “archery bow sling and cover apparatus,” as shown and described.

DESCRIPTION

FIG. 1 is a top perspective view, rotated 90°, of an “archery bow sling and cover apparatus” according to the present invention;

FIG. 2 is another top perspective view of an “archery bow sling and cover apparatus” according to the present invention;

FIG. 3 is a bottom perspective view of an “archery bow sling and cover apparatus” according to the present invention;

FIG. 4 is an end view of an “archery bow sling and cover apparatus” according to the present invention; and,

FIG. 5 is the opposite end view of an “archery bow sling and cover apparatus” according to the present invention.

The broken lines are for illustrative purposes only and form no part of the claimed design.

The dotted lines on the straps are understood to represent stitching.
